OTTO C. AHLBORN, OF HILDERSHEIM, GERMANY.

PUMP.

1,099,155.

Specification of Letters Patent.

Patented June 9, 1914.

Application filed March 7, 1911. Serial No. 612,739.

To all whom it may concern:

Be it known that I, OTTO C. AHLBORN, a subject of the Emperor of Germany, residing at Hildersheim, Hanover Province, 5 Germany, have invented certain new and useful Improvements in Pumps, of which the following is a specification.

My present invention relates to improvements in pumps and particularly to those 10 of the so called "valveless" type, and it has for its object to provide a simple, improved and efficient pump of this character wherein the piston not only serves to introduce and discharge the liquid or fluid, 15 but also serves as a valve to control the introduction and discharge of the liquid or fluid, the piston being constructed and operated in such a manner that the pump will be double-acting, that is to say, it will introduce and discharge volumes of liquid or fluid during each stroke of the piston, a 20 pump of relatively large capacity being thereby provided and a substantially continuous discharge is insured.

Further objects of the invention are to 25 provide a pump of this character wherein the piston, cylinder and related parts are so constructed and assembled that they may be cleaned thoroughly and with facility, a 30 sanitary pump being thereby provided which is especially adapted for use in connection with milk.

To these and other ends, the invention 35 consists in certain improvements, and combinations and arrangements of parts, all as will be hereinafter more fully described, the novel features being pointed out particularly in the claims at the end of the specification.

In the accompanying drawing: Figure 1 40 illustrates a pump constructed in accordance with one embodiment of my invention, the pump being shown partly in side elevation and partly in section; Fig. 2 represents a front elevation of the pump as 45 shown in Fig. 1; Figs. 3, 5, 7 and 9 are diagrammatic views showing the cycle of operations of the pump; Figs. 4, 6, 8 and 50 10 are diagrammatic views showing the different relations between the ports of the piston and cylinder corresponding respectively to Figs. 3, 5, 7 and 9; and Fig. 11 is a detail sectional view of the operating device for the piston.

Similar parts are designated by the same 55 reference characters in the several views.

In the present embodiment of the invention, the pump embodies a frame 1 of any suitable design and construction, the frame in the present instance having a base 2, a 60 bearing pedestal 3, an arm 4 to support the pump cylinder, and a bearing 5 for guiding the piston rod. The frame 1 and the pedestal 3 support suitable bearings for a driving shaft 6, this shaft being equipped with 65 tight and loose pulleys 7 and 8 whereby the pump may be driven, for example, by a belt and in such cases a belt shifter 9 may be provided for controlling the operation of the pump.

A wrist plate or its equivalent 10 is fixed 70 to the shaft 6 and this wrist plate embodies means whereby the pump piston is operated. In the preferred form of the invention, the operating means for the piston 75 comprises a substantially spherical head or ball 11 which is fitted to oscillate in a correspondingly formed seat, a part 12 of the seat being formed in the wrist plate 10 while the other part 13 of the seat may be 80 formed upon a flanged ring 14, and this ring may be detachably or otherwise secured to the face of the wrist plate 10. Screws 15 are shown in the present instance which enable the ring to be readily applied 85 and removed if necessary with respect to the wrist plate and this removably applied ring provides means whereby the spherical head may be mounted in its seat. The head 11 is provided with a bore 16 which 90 preferably extends diametrically therethrough and a driving pin 17 is fitted in the bore 16 in such a way that it may move axially and also rotate with respect to the head 11. The outer end of the pin 17 is 95 rigidly secured in a head 18 which is formed upon the upper end of a guide rod 19, the lower end of this guide rod operating vertically in the bearing 5 so that the guide rod is permitted to operate only in a 100 rectilinear direction, the axis of the guide rod preferably intersecting the axis about which the head 11 revolves during rotation of the pump driving shaft.

The pump cylinder is preferably mounted 105 on and supported by the arm 4 of the frame. To facilitate the assembling and taking apart of the pump for cleaning and other purposes, the cylinder is preferably formed as a body section 20 and has separate and 110 detachable upper and lower heads 21 and 22. The lower head 22 is preferably seated re-

movably in a recess 23 formed in the top of the arm 4 and it is equipped with a stuffing box or packing device 24 for the piston rod, this stuffing box extending through an opening 25 formed in the arm 4 and centrally of the seat 23. The upper cylinder head 21 may be formed with a flange as shown for the purpose of centering it upon the top of the body section of the cylinder and the several detachable parts of the cylinder are firmly united to one another and to the frame of the pump by means of a yoke 26 the two ends of which are pivotally attached to the upper portion of the arm 4 of the pump frame by means of the pivot bolts 27 and the intermediate portion of the yoke is provided with a clamping screw 28 which may for convenience be formed with a handle at its upper end and its lower end bears in a central seat 29 formed in the top of the upper cylinder head 21. When the different parts of the cylinder are assembled, they are firmly united by tightening the screw 28 while the yoke is in vertical position. By loosening the screw 28, however, the yoke 26 can be swung to an inoperative position, the compression upon the different sections of the cylinder will be relieved, and the pump can be readily cleaned by removing such parts of the cylinder as necessary for the purpose.

According to the present invention, the use of separate valves which are objectionable for well known reasons and render a pump difficult to clean when handling milk, is avoided, the pump piston in the present instance being so constructed and operated that it will not only introduce and discharge the liquid at each stroke, but it will also rotate on its axis and thereby control the admission and discharge of the liquid. In that form of the invention shown, the piston 30 is substantially cylindrical and has a suitable fluid-tight fit within the body of the cylinder, it being capable of reciprocating and also rotating therein. The piston is provided with a piston rod 31 which extends through the stuffing or packing box 24 and the lower end of the piston rod is suitably attached to the driving head 18 so that the piston rod will be reciprocated and also rotated according to the movements of said head. For example, the piston rod may be rigidly secured to the head 18 by a pin 32. The body of the piston is formed with one pair of vertical chambers or ports 33 and 34, these chambers or ports being open at the corresponding side of the piston and are open at the top of the piston and closed at the bottom thereof, and the piston is also formed with a second pair of vertical chambers or ports 35 and 36 which are closed at the top of the piston and open at the bottom. Preferably, the two pairs of chambers or ports in the piston are distributed or ar-

ranged equidistantly in a circumferential direction, the two chambers or ports 33 and 34 which are open at the top of the piston being adjacent to one another and arranged at one side of the piston while the chambers or ports 35 and 36 which are open at the bottom of the piston are adjacent to one another and occupy a position at the opposite side of the piston. The cylinder section 20 is provided with an inlet port 37 and an outlet or discharge port 38, these ports being suitably placed according to the location and position of the ports or chambers in the piston. In the present instance the inlet and outlet ports in the cylinder section are arranged diametrically opposite and midway of the length of the cylinder.

In operation, the piston is reciprocated and is also rotated about its geometrical axis by the head 11, pin 17, the wrist plate 10 and related parts and, during the operation of the pump, one charge of fluid is introduced into the cylinder and another charge of fluid is exhausted therefrom at each stroke of the piston. This result is accomplished as follows: Assuming that the piston is at the end of its up-stroke, the driving pin 17 will then occupy a position directly above the axis of rotation of the wrist plate 10 and the pin 17 will be parallel to the axis of rotation of the wrist plate 10. Figs. 3 and 4 show the relation of the ports or chambers of the piston to those of the cylinder when the piston is at the limit of its up-stroke, the inlet and exhaust ports 37 and 38 of the cylinder being at this moment closed. As the wrist plate 10 rotates to move the piston on its down-stroke, an angular movement will be imparted to the driving pin 17 owing to the fact that the head 11 which is co-operative with this pin travels in a circular path while the piston rod to which the outer end of the pin is connected reciprocates in a rectilinear direction. The angular position assumed by the driving pin will therefore rotate the piston and thereby cause the chamber or port 34 which opens at the top of the piston to be presented to the inlet port 37 of the cylinder and during the down-stroke of the piston, a charge of liquid or fluid will be introduced through the ports 37 and 34 to the upper side of the piston. During the down-stroke of the piston, the chamber or port 35 therein which opens at the bottom of the piston will be brought into registration with the outlet or exhaust port 38 of the pump and as the piston descends, a charge of liquid or fluid at the under side of the piston will be exhausted through the chamber or port 35 in the piston and the outlet port 38 of the cylinder, the relation of the piston and cylinder during the down-stroke of the piston being shown diagrammatically in Figs. 5 and 6. When the

piston reaches the limit of its down-stroke, the driving pin 17 will again assume a position in parallelism with the axis of rotation of the wrist plate 10 and the piston 5 will be rotated in a reverse direction and will close the inlet and discharge ports 37 and 38 of the cylinder, as shown diagrammatically in Fig. 8. When the driving pin passes its center and begins its upward 10 movement, the piston will be rotated into the position shown diagrammatically in Figs. 9 and 10, this position of the piston being reverse to that shown in Figs. 5 and 6. When the piston is in this position, the 15 chamber or port 33 which opens at the top of the piston will be brought into communication with the exhaust port 38 of the cylinder while the chamber or port 36 which opens at the bottom of the piston will be 20 brought into communication with the inlet port 37 of the cylinder and during the up-stroke of the piston, the charge of liquid previously introduced into the upper end of the cylinder above the piston is exhausted 25 through the chamber or port 33 and the discharge port 38 and at the same time another charge of liquid or fluid will be introduced into the lower end of the cylinder and beneath the piston through the inlet port 37 of the cylinder and the chamber or port 36 of the piston, the cycles just 30 outlined being repeated during the operation of the pump. As the pump is double-acting in its operation, the liquid or fluid 35 will flow to and from the pump with a substantially continuous motion.

I claim as my invention:

1. In a pump of the character described, the combination of a frame having a seat formed thereon, a cylinder head resting on 40 said seat, a cylinder open at both ends and resting on said head, a second cylinder head formed separately from and resting on the upper end of said cylinder, and a clamp connected to said frame and operative upon 45 the said second head to firmly secure the cylinder and its heads in operative relation and for securing said parts as a unit to said frame.

2. In a pump, the combination of a frame 50 having a seat, a head resting on said seat, a cylinder open at both ends and resting on said head and having inlet and exhaust ports arranged in the sides thereof, a piston operative in said cylinder and having ports 55 coöperative with those of the cylinder to control the introduction and discharge of fluid with respect to the cylinder, a second head formed separately from and resting on the opposite end of the cylinder, and a 60 clamp connected to the frame and operative upon said second head to secure said heads and cylinder to one another and to the frame.

In testimony whereof I have hereunto set 65 my hand in presence of two subscribing witnesses.

OTTO C. AHLBORN.
